UNITED STATES PATENT OFFICE.

HUGH W. PEIGHTAL, OF DENVER, COLORADO.

WINDOW-SCREEN.

SPECIFICATION forming part of Letters Patent No. 767,433, dated August 16, 1904.

Application filed December 23, 1903. Serial No. 136,387. (No model.)

To all whom it may concern:

Be it known that I, HUGH W. PEIGHTAL, a citizen of the United States of America, residing in the city and county of Denver and State 5 of Colorado, have invented certain new and useful Improvements in Window-Screens; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 My invention relates to improvements in window-screens having a metal frame, and relates more particularly to the special construction of frame, also to means for fastening the gauze or wire mesh to the frame, and, 20 further, to a protecting-molding which conceals the fastening-clips and also the outer edge of the gauze material.

Having briefly outlined my improved construction, I will proceed to describe the same 25 in detail, reference being made to the accompanying drawings, in which is illustrated an embodiment thereof.

In the drawings, Figure 1 is a front view of my improved window-screen shown on a 30 small scale. Fig. 2 is a fragmentary view showing one corner of the screen on a larger scale. Fig. 3 is a section taken on the line 3 3, Fig. 2. Fig. 4 is a top or plan view of the inner extremity of the fastening-clip shown 35 on a larger scale. Fig. 5 is a section taken on the line 5 5, Fig. 4.

The same reference characters indicate the same parts in all the views.

Let A designate side and end sections of 40 the frame, which are united at the corners by overlapping, as shown at A'. Each of these sections is formed from a sheet-metal plate consisting of a flat face A², a portion A³, bent back against the under surface of the part A² 45 and extending inwardly to a point A⁴, whence the plate is bent at right angles to the part A³, as shown at A⁵, and extends rearwardly to a point A⁶, where it is bent and extends forwardly at an angle of about forty-five degrees with the part A⁵, as shown at A⁷. The

part A⁷ extends to a point A⁸, whence it is bent to form an obtuse angle, and extends inwardly parallel with the face-plate A² to a point A⁹, where it is bent down upon the face-plate A², as shown at A¹⁰. At the inner extremity A¹¹ of the face-plate A² the latter is bent rearwardly and pressed down upon the rear surface of the plate A², as shown at A¹². Where the parts of the plate are folded against each other in the construction of the frame, 60 the said parts are secured by the use of solder.

Parallel slits A¹³ are formed in the face-plate A², and the material between these slits is punched forwardly to form a loop A¹⁴, through which a fastening-clip A¹⁵ may be 65 passed. This clip extends transversely to the direction of the side or end frame-section, and its inner extremity is bent to hook into the wire gauze or mesh material, as shown at A¹⁶. The outer portion A¹⁷ of the clip after the 70 gauze has been drawn sufficiently taut is bent over upon the loop A¹⁴, as best shown at the right of Fig. 2, where the molding is broken away.

The metal molding B consists of side and 75 end strips B', cut to form miter-joints at the corners, as shown at B². These sections B' are fastened to the body of the frame by means of screws C, which are passed through openings in the outer part of the molding and 80 threaded in the parts A² and A¹² of the frame, which is double the thickness of the frame-plate at this point. This molding conceals the outer or rough edge of the wire gauze or 85 mesh and also the clips which secure the gauze to the frame after the said clips are attached or applied, as indicated in the drawings.

Attention is called to the fact that the metal frame of the window-screen is practically inde- 90 structible and will outwear a great many pieces of wire-gauze. To remove the wire-gauze, it is only necessary to unscrew the screws C and remove the molding-sections B'. The parts A¹⁷ of the clip may then be bent flat upon 95 the face of the frame, after which the clips may be pulled inwardly through the loops and released from the wire-gauze. These clips may then be used with another piece of gauze or wire mesh material, since the clips are made 100

of soft metal and will stand considerable bending without breaking. The molding-strips B' may then be placed in position and secured by the fastening-screws C.

5 Attention is called to the fact that the holding extremity A¹⁶ of the fastening-clips is transversely curved where it engages the gauze or wire mesh, in order to give an arc-shaped bearing for the wire, as distinguished 10 from a bearing having sharp edges over which the wire passes, as would be the case if the clip were transversely flat where it engages the wire.

Attention is also called to the fact that the 15 fastening-clips are made of considerable length, as shown at the left of Fig. 2, in order that their outer extremities may be utilized to give considerable tension on the gauze or wire mesh. By reference to the drawings it 20 will be seen that by making the clip of considerable length a better opportunity is afforded for drawing the gauze taut than would be the case if the clip were short outside of the loop. After the clip has been drawn out- 25 wardly to give the wire gauze or mesh the desired tension the superfluous portion of the clip is removed after the clip has been bent down upon the loop, as shown at the right of Fig. 2.

30 Having thus described my invention, what I claim is—

1. A metal frame for window-screens, composed of side and end sections connected together at the extremities, each of said sections being formed from an integral metal plate 35 formed double a portion of its distance, and bent to form a strengthening-rib on the side opposite the face of the frame, the double portion of the said face being provided with 40 threaded openings; and molding-strips ap-

plied to the side and end sections of the frame and fastened by screws passed through the molding and threaded in the double portion of the face.

2. A window-screen composed of a metal 45 frame and wire gauze or mesh material, the frame being provided with loops on its face or front side, fastening-clips passed through the loops, their inner extremities being turned upwardly to catch the wire gauze or mesh, and their outer extremities being bent upon the loops to hold the clips securely in place. 50

3. In a window-screen, the combination of a metal frame provided with wire mesh or gauze, the face of the frame being provided 55 with loops, clips passed through the loops and having their inner extremities bent to catch the wire mesh or gauze, their outer extremities being bent to fasten the clips in place, and metal molding-strips applied to the side and 60 end sections of the frame and suitably secured in place.

4. The combination of a metal frame provided with wire gauze or mesh for a window-screen, the said frame being provided with 65 loops punched out of the metal on the face-plate side, whereby the loops are integral with the face of the frame, and clips passed through the loops and engaging the face of the frame, the inner extremities of the clips being bent 70 to catch the wire gauze or mesh, their outer extremities being bent to secure the clips in place.

In testimony whereof I affix my signature in presence of two witnesses.

HUGH W. PEIGHTAL.
